UNITED STATES PATENT OFFICE

FRITZ MERZ, AND ADOLEF FRITZ SCHAUSS, OF FRANKFORT-ON-THE-MAIN-RODELHEIM,
GERMANY

MACHINE FOR FASTENING WITH WIRE STAPLES

Application filed February 27, 1930, Serial No. 431,861, and in Germany June 4, 1928.

The invention relates to a hand stapling machine for fastening papers and the like by means of wire staples. A reel of wire inserted in the machine contains the wire for forming the staples. When the machine is operated it automatically cuts off from the reel a length of wire corresponding to a staple, shapes the same and then by means of a driver, forces it through and bends it round the material to be fastened.

The invention will be clearly understood from the following description aided by the annexed drawings in which a typical embodiment of the new stapling machine is illustrated.

Fig. 1 is a longitudinal section through the machine.

Fig. 2 is a plan of same with the outer cover of the tool chamber detached.

Figs. 3 to 6 represent a section along the line 3—3 of Fig. 2, with the several parts in their various positions during the course of the operation.

Figs. 3a to 5a show the positions of the several parts corresponding to those in Figures 3 to 5, in a section along the line 3a—3a of Fig. 2.

Fig. 7 is a perspective view of the members which shape and drive the staples.

Fig. 8 is a part of that jaw of the machine which serves as anvil.

Fig. 9 is a horizontal section through the chamber b above the guide for the wire.

As can be seen from Figures 1 and 2, the open ends of the mouth of the new machine according to the invention are bent at an angle in relation to the plane of the machine for the purpose of enabling the machine to be moved along the fastening margin and the margin of papers or the like, of any convenient dimensions, to be guided through the machine and stapled (Figure 2). The upper limb a is forked in front and rear of the pivotal axis c and carries on its free end, the anvil or plate a¹ (Figure 8) serving as a support for the material to be fastened and for the staples. The other limb which carries the tools for forming the staples, consists of two parts which also are forked at the pivotal axis c. The member b containing the tools

forms a chamber which is pivotally mounted in the forked portion of the limb a and together with the handle d is secured on the pivot c by means of bearing lugs b¹. An arm b² provided on the casing b and projecting rearwardly between the limbs carries the stock reel of wire e. In the vicinity of its pivotal axis, the handle is provided with two upwardly extending arms d¹ and d², which project through the bottom into the chamber b and actuate the tools and form the staples (Figure 2) when the handles of the machine are caused to converge by squeezing.

The rearwardly extending arm b³ is forked at the ends to accommodate the reel e of wire and each portion is provided with slots or the like e², in which the axis of the reel is inserted. A forked pawl e¹ mounted at b³ on the arm b² bears against the axis of the reel by means of its forked ends under the action of a spring and holds same in the slots e². A coiled spring f, disposed between the arm b³ and the handle d holds the parts of the machine in the position of engagement shown in Figure 4, in which the arms of the limb d bear at x against the cover b⁷ of the casing (Figure 1). A weaker spring f¹ engages at one end on the lever d and at the other end with the limb a, which it causes to bear at y against the casing b or the rear part of the cover, thus determining the opening of the jaws.

The staples are formed in the chamber b, which is divided by a partition into the chamber b⁴ situated in the bent portion and a larger portion. In the forwardly situated smaller chamber space b⁴ are slidably disposed (see Figure 2) the staple formers g¹ and g² together with the driver h¹ (Figure 7). The driver consists of a driving plate h¹ of the same width as the staples and the formers g¹ and g² are disposed on either side, near the driver. In order to enable both parts to undergo relative displacement, two sliding members g and h are disposed face to face in the casing of the chamber (Figures 3a to 5a) at a distance corresponding to the thickness of the former and driver plates. The member g carries the externally disposed former plates g¹ and g² and the

55

60

65

70

75

80

85

90

95

100

member h carries the driver h^1 . The members g^1 and g^2 are chamfered and as herein-after described, the one plate can serve as a cutter. When the two sliding members are superimposed the driver h^1 lies between the members g^1 and g^2 . The sliding members are preferably inserted in a frame g^3 , the under portion of which is provided with a feed channel for the binding wire k . The sliding members g and h are provided with an opening or are designed in such a way that each of the rocking levers i and j is adapted to engage one of said members through the partition. The rocking levers depress the sliding members with the parts g^1 , g^2 and h^1 in such a way that the sliding member g with the plates g^1 and g^2 moves ahead, so that they can detach a length of wire and bend the ends of same into a staple over an abutment l (Figure 4).

The heads i^1 and j^1 of the levers i and j each project through a slot in the partition into the sliding members g and h respectively. The wire k is fed from the reel by a device to be described later, into the discharge opening b^5 of the chamber b^4 (Figures 3, 3a and 9) into which opening projects the abutment l , which is secured on the casing b by means of a flat spring l^1 or the like and can be moved out of the way of the wire feed device.

The manner in which the machine operates in shaping the staples can be seen from Figures 3 to 6 and the corresponding Figures 3a to 5a. At the beginning of the operation the machine or its parts occupy the position shown in Figures 3 and 3a. When the limbs of the machine are caused to converge the movement is transmitted through the arms d^1 and d^2 , which act on the levers i and j , to the sliding member g and staple driver in the manner hereinafter described, so that at first, only the member g is advanced. In this advancing movement of the former, the plate g^2 cuts off a piece of wire of the length of the staple to be formed. This wire is then bent round the abutment l into a U staple by the chamfered plates g^1 and g^2 during their further advance, the position being shown in Figures 4 and 4a.

During the further convergence of the machine, the staple driver h^1 now advances, whereas the formers g^1 and g^2 remain stationary. The plate h of the driver h^1 carries a pin h^2 , the point of which is chamfered or wedge shaped and which projects out of the wall of the chamber b^4 (Figures 4a and 5a). The limb of the abutment l is provided with a hole of the same diameter as the pin h^2 , but disposed in such a manner that the pin during its descent slides by means of its oblique end surface on the edge of the hole and moves the abutment l away from the opening b^5 (Figures 5 and 5a). In the meantime the driver plate h^1 is moved forward simultaneously with the pin h^2 (being mount-

ed on the same sliding member h) and during its descent forces the staple out of the opening b^5 and through the underlying material which is to be fastened. When the machine is in the fully closed position the tips of the staple encounter the anvil a^1 or the recesses a^2 and are bent over as shown in Figure 6.

As already mentioned, the movement of the staple former and driver during the closing of the machine is effected by the limbs d^1 and d^2 of the handle d . For the purpose of transmitting the movement, the levers i and j are mounted on a pivot in the casing b . The flat round heads i^1 and j^1 of these levers engage in the sliding member g and h . The other arms of the levers i and j slide over the correspondingly curved end surfaces of the limbs d^1 and d^2 , the curvature of which is such that in the act of closing the machine that portion of the lever i which engages in the member g is swung out first and is followed after a certain stroke, by the sliding member which carries the driver h^1 . The curvature of the limb d^1 is such that the lever i ceases to swing as soon as the swinging movement of the lever j coupled with the driver h commences. This can be easily seen from Figure 1.

The levers i and j are returned into neutral position by means of spiral spring i^2 , j^2 mounted on the casing at b^6 and acting on said levers. The arms i^3 and j^3 projecting through slots in the casing serve for the examination and actuation of the levers by hand in the event of seizing or the like.

The wire is fed forward intermittently with the opening and closing of the machine and the movement of the tools for forming the staples and the feeding is timed so that in opening the jaws of the machine, a sufficient length of wire to form a staple is moved into position under the tools. For this reason the feed device is connected with one of the levers for actuating the tools, namely the lever i in the embodiment described. The wire k coming from the reel is led through guide tubes o , p and q (the latter being tapered) into the gap b^5 . The central member p of the tubes is adapted to slide over the tube o and inside the tube q , or vice versa. A flat spring o^1 in the tube o is intended to prevent the wire from slipping back when once in position. As can be seen from Figure 9, the wire guide is disposed on one side of the chamber b and in the direction of the compartments of the chamber b , thus enabling the front end of the wire to be introduced for the purpose of forming the staple into the middle of the guide b by deflecting the guidance of the wire without interfering with the actuation of the tool. Hence the wire reel can be disposed directly in the plane of the ascending and descending members and the wire fed in their direction, whilst the

staple formed from the wire is set in a diverted plane by the tools.

As shown more particularly in Figure 1, the member *p* carries a pivotally mounted clamping or cam lever or a two-armed pawl *r*. The free end of the lever is engaged by a drawbar *s* which, in its rearward movement, first tilts backwards and with the tube *p* slides over the wire *k* contained in that tube. During its forward movement the clamping lever rises, holding the wire against the tube *p* and carrying them both with it. The advance and retreat of the tube *P* and pawl *r* engaged by the drawbar *s* are effected by the lever *i*. For this purpose there is mounted in the casing *b* in front of the pivotal axis of the levers *i* and *j*, a spring controlled lever *n* which is mounted on the pivotal axis *n*¹ and carries on its downward arm the drawbar *s*. A spiral spring on the axis *n*¹ tends to turn the lever *n* and with the aid of the bar *s* to maintain the pawl *r* and tube *p* in the forward position. Pivotally mounted in front of the axis *n*¹ is a two-armed lever *m*, the one arm of which engages under a nose *n*² on the lever *n* and is guided by means of a pin *m*² on the other arm in a slot *m*¹ in the lever *i*. It will be evident that in descending, the front end of the lever *i* or *i*¹, the pin *m*² is also moved and swinging out the lever *m* causes the nose *n*₂ to turn the lever *n*, so that the bar *s* and tube *p* are pushed against the action of the spring disposed on the axis *n*¹. In this movement the cam of the lever *r* slides over the wire *k*. As soon, however, as the lever *i* swings back again, its rear arm moves away from the nose *n*² and the lever *n* is able under the influence of its spring, to exert a pull on the bar *s* and pawl *r*, which clamping the wire, draws the latter and tube *p* as far as the stop, thus feeding a portion of wire of the length of a staple under the tools. This operation is repeated each time the tools allow access over the anvil or in the gap *b*⁵.

The method of operation will be evident from the description, when the papers to be fastened are inserted in the jaws of the machine, the latter is closed by squeezing the handles. This causes the levers *i* and *j* to move and insert the staples in the manner described. The movement of the lever *i* causes the lever *m* and *n* positively connected therewith to describe an anticlockwise movement. The movement of the lever *n* is transmitted by the bar *s* to the cam lever *r* and tube *p*. During the subsequent opening of the machine, the wire is fed forward. Since, in the meantime, the discharge opening has been freed by the ejection of the pre-formed staples, the wire is free to enter said opening and the machine is then ready for the next working operation.

We claim:

1. A hand stapler of the plier type in which

staples are automatically detached and formed, when the jaws of the pliers are closed, a casing pivotally mounted on the pivot of the jaw members and carrying staple forming and setting members, said casing carrying a wire reel, one of the jaws being forked at its free end to form operating cams, and levers operated by the said cams for actuating the staple forming and setting members. 70

2. A hand stapler of the plier type in which staples are automatically detached and formed when the jaws of the pliers are closed, a casing pivotally mounted on the pivot of the jaw members and carrying staple forming and setting plungers, said casing having a wire reel on its rear end, one of the jaws being forked at its free end to form operating cams, and levers operated by said cams for actuating the staple forming and setting plungers. 80

3. A hand stapler of the plier type in which staples are automatically detached and formed when the jaws of the pliers are closed, a casing pivotally mounted on the pivot of the jaw members and carrying staple forming and setting tools, the ends of the mouth of the machine being bent at an angle and the forming of the staples being effected in this bent portion, one half of the mouth of the machine forming the casing in which are combined the staple forming and staple driving tools, the discharge opening of the chamber housing the staple former being provided with a recess in which an abutment surface which projects into the said opening 95 and serves to form the staples, is forced back by the driver during its descent. 100

4. A hand stapler of the plier type in which staples are automatically detached and formed when the jaws of the pliers are closed, a casing pivotally mounted on the pivot of the jaw members and carrying staple forming and setting tools, the ends of the mouth of the machine being bent at an angle and the forming of the staples being effected in this bent portion, one half of the mouth of the machine forming the casing in which are combined the tools for forming the staples and the staple driver, the staple former consisting of a sliding member carrying two plates disposed at a distance corresponding to the width of a staple and having their free ends chamfered and the staple driver consisting of a sliding member carrying a 115 driver plate of the width of the staple to be formed said tools being inserted and actuated in the bent part, in order that the driver plate can be guided between the plates of the staple former and describe a movement relatively to the staple formers preceding it, the discharge opening of the chamber housing the staple former being provided with a recess in which an abutment surface which projects into the said opening and serves to 120

form the staples, is forced back by the driver during its descent.

5. A hand stapler of the plier type in which staples are automatically detached and formed when the jaws of the pliers are closed, a casing pivotally mounted on the pivot of the jaw members and carrying staple forming and setting tools, one half of the mouth of the machine forming said casing, said 10 casing being mounted on pivotal axis of the machine and carrying the wire reel on its rear end, the wire coming from the reel passing to the tools through a divided tube, one member of which is adapted to slide and 15 carries a clamping lever projecting into the tube and engaged by a draw bar which is coupled with and actuated by the levers actuating the tools.

6. A hand stapler of the plier type in which 20 staples are automatically detached and formed when the jaws of the pliers are closed, a casing pivotally mounted on the pivot of the jaw members and carrying staple forming and setting tools, one half of the mouth 25 of the machine forming said casing, said casing being mounted on pivotal axis of the machine, and carrying the wire reel on its rear end, whilst being supported against one limb of the machine by a spring and being 30 pivotally mounted in the other limb, the wire coming from the reel passing to the tools through a divided tube, having a member adapted to slide and carrying a clamping 35 lever which projects into the tube and is engaged by a draw bar which is coupled with and actuated by the levers actuating the tools.

7. A hand stapler of the plier type in which staples are automatically detached and formed when the jaws of the pliers are closed, 40 a casing pivotally mounted on the pivot of the jaw members and carrying staple forming and setting tools, the ends of the mouth of the machine being bent at an angle, one half of the mouth of the machine forming 45 said casing, the staple former consisting of a sliding member carrying two plates disposed at a distance corresponding to the width of a staple and having their free ends chamfered and the staple driver consisting of 50 a sliding member carrying a driver plate of the width of the staple to be formed and these two tools being inserted and actuated in the bent part, in order that the driver plate can be guided between the plates of the staple 55 former, and describe a movement relatively to the staple formers preceding them, the discharge opening of the chamber housing the staple former being provided with a recess in which an abutment surface which projects 60 into the said opening and serves to form the staples, is forced back by the driver during the descent, the wire coming from the reel passing to the tools through a divided tube, one member of which is adapted to slide and 65 carries a clamping lever projecting into the

tube and engaged by a draw bar which is coupled with and actuated by the levers actuating the tools.

8. A hand stapler of the plier type in which staples are automatically detached and formed when the jaws of the pliers are closed, 70 a casing pivotally mounted on the pivot of the jaw members and carrying staple forming and setting tools, one half of the mouth of the machine forming said casing, this end 75 of the mouth of the machine being bent at an angle, a lever actuating the staple former and engaged by a two-armed lever adapted to, on the descent of the lever, impart a positive rearward swing to a spring controlled lever feeding a portion of wire to the staple former.

9. A hand stapler of the plier type in which staples are automatically detached and formed when the jaws of the pliers are closed, 80 a casing pivotally mounted on the pivot of the jaw members and carrying staple forming and setting tools, one half of the mouth of the machine forming the casing in which 85 are combined the tools for forming the staples, this end of the mouth of the machine being bent at an angle, the wire coming from a reel on the said casing passing to the staple forming and setting plungers through a divided tube having a slidable member carrying 90 a clamping lever which projects into the tube and is engaged by a draw bar, a lever actuating the staple former and engaged by a two-armed lever which, on the descent of the lever, imparts a positive rearward swing 95 to a spring controlled lever, said lever being actuated to draw forward the draw-bar with the clamping lever and the slidable tube in order to feed in the forward direction a portion of wire corresponding to the 100 length of a staple.

10. A hand stapler of the plier type in which staples are automatically detached and formed when the jaws of the pliers are closed, 110 a casing pivotally mounted on the pivot of the jaw members and carrying staple forming and setting tools, the ends of the mouth of the machine being bent at an angle, one half of the mouth of the machine forming 115 said casing, the staple former consisting of a sliding member carrying two plates disposed at a distance corresponding to the width of a staple and having their free ends 120 chamfered and the staple driver consisting of a sliding member carrying a driver plate of the width of the staple to be formed and these two tools being inserted and actuated in the bent part, in order that the driver plate can be guided between the plates of the staple former and describe a movement relatively 125 to the staple formers preceding them, the discharge opening of the chamber housing the staple former being provided with a recess in which an abutment surface which projects into the said opening and serves to form the 130

staples, is forced back by the driver during the descent, the wire coming from a reel on the rear end of the casing enclosing the tools and passing to the tools through a divided tube, one member of said tube being adapted to slide and carrying a clamping lever which projects into the tube and is engaged by a draw bar, the lever actuating the staple former being engaged by a two-armed lever which, on the descent of the lever imparts a positive rearward swing to a spring controlled lever adapted to draw forward the draw-bar with the clamping lever and the slideable tube in order to feed in the forward direction a portion of wire corresponding to the length of a staple.

11. A hand stapler of the plier type in which staples are automatically detached and formed, when the jaws of the pliers are closed, a casing pivotally mounted on the pivot of the jaw members and carrying staple forming and setting members, one of the jaws being forked at its free end to form operating cams, and levers operated by the said cams for actuating the staple forming and setting members.

FRITZ MERZ.
